UNITED STATES PATENT OFFICE.

VICTOR W. MOORE, OF ATHENS, GEORGIA.

PRYING DEVICE.

1,310,538.

Specification of Letters Patent.

Patented July 22, 1919.

Application filed March 10, 1917, Serial No. 153,970. Renewed February 25, 1919. Serial No. 279,180.

To all whom it may concern:

Be it known that I, VICTOR WALLACE MOORE, a citizen of the United States, residing at Athens, in the county of Clarke and State of Georgia, have invented certain new and useful Improvements in Prying Devices, of which the following is a specification.

My invention relates to a device for separating the parts of shock-absorbers and more particularly for separating the leaves of shock-absorbing leaf springs.

The principal object of the present invention is to provide a leaf spring separator which may be quickly, effectively and readily engaged with the leaf spring to separate the leaves thereof with little physical effort.

A second object of the invention is to provide a device or implement of this general character which may be used to separate the leaves of the leaf spring or to stretch a coil spring, or in fact may be used for separating any two closely assembled parts.

A further object of my present invention provides an implement of this character which may be adjusted so that the same may be used in connection with any width of leaf spring or other objects and the parts of which are to be separated.

An additional object of the invention is to provide a leaf spring spreader which consists of few cooperating parts and is easily adjusted, assembled and manufactured and which is highly efficient and durable and can be manufactured and placed on the market at a minimum cost.

The above general objects and others and the advantageous features of my improved leaf spring spreader will be set forth in the following specification and claimed therein.

On the drawing:

Figure 1 is a side elevation of my device in operative and inoperative positions, full lines indicating the inoperative or separating position and the dotted lines indicating the operative position; parts of the device and the leaf springs being shown in section.

Fig. 2 is an end elevation looking from the end having the bearing arms thereon and,

Fig. 3 is a transverse sectional view on the line 3-3 of Fig. 1.

Referring to the drawings the numeral 5 designates a longitudinal bar which is preferably rectangular in cross section and is formed of any desirable material possess-

ing the desired strength. This bar is formed with a right-angular extension which is bifurcated or cut out to provide bearing-arms 6 in which is rotatably mounted a 60 stub shaft 7 having fixed to rotate therewith an eccentric 8 which is secured to the shaft 7 by a fastening screw 9. This shaft 7 is formed with a circular enlargement 10 having a transverse opening 11 in which is 65 mounted a rod or operating handle 12 which is of the usual construction and has the usual stop heads 13.

Pivotedly mounted on the bar 5 adjacent to the bearings 6 is a vertically extending arm 14 which arm is bifurcated to provide bearing-ears which bearing-ears are adapted for pivotal movement on the pin 15 passing through this bar 5. This arm 14 is provided with a recess 16 which receives one 70 end of a coil spring 17 that extends within a similar recess 18 in the bar 5 and the normal tendency of which is to retain this arm 75 in the dotted line position in Fig. 1.

The under face of the bar 5 is provided 80 with transverse ribs, serrations or teeth 19. An arm similar to the arm 14 is longitudinally adjustable on the bar 5 and is designated by the numeral 20. This arm 20 is 85 bent at an oblique angle with respect to the longitudinal axis thereof at its lower end as indicated by the numeral 21 which oblique end is cut out so as to receive the bar 5 and is connected or formed with a cross-bar 22. This cross bar 22 carries or is formed 90 with a transverse extending rib 23 which is adapted for engagement in the notches between the transversely extending teeth 19 to 95 retain the arm 20 in the position shown in full lines in Fig. 1.

The arms 20 and 14 are formed with 100 barbs or tapering lugs 24 which extend toward each other and are adapted to be engaged between a pair of leaves of a leaf spring. For the purpose of illustration the leaf spring is shown which is designated by the letter A.

The operation of my improved leaf spring separator is as follows: In order to adjust 105 the arm 20 to the desired position it is moved to the dotted line position shown in Fig. 1 and moved until the barb 24 which is carried thereby is arranged at the longitudinal edges of a pair of the sections and 110 at a point where they contact with the edge thereof. The handle 12 is now rotated to

rotate the eccentric 8, which eccentric engages the arm 14 and rocks the same which causes the barb 24 to enter between two leaves of the leaf spring, separating the same.

5 This disclosure is merely for the purpose of setting forth a preferred embodiment of the invention. It is to be understood that the inventive idea can be carried out in constructions other than the one herein disclosed and that the structure herein set forth may be modified and altered in many respects that I may be entitled to by the herewith appended claims.

What is claimed is:

15 1. A device as described, comprising a toothed bar, an arm pivotally secured thereto, a rotatable eccentric supported by said bar and engaging said arm, a spring engaging said arm to hold the same against 20 said eccentric, a second arm provided at its lower end with an opening to receive said bar, a locking rib extending across the bottom wall of said opening and engageable with the teeth formed in said bar, and wedge 25 members carried by said arms.

2. A device of the character described comprising an elongated bar having teeth formed thereon, an arm slidably mounted on said bar and carrying a rib adapted for

locking engagement with said teeth, a second 30 arm pivotally secured to said bar and opposing said first arm, resilient means engaging said pivoted arm and urging the same in a direction away from said sliding arm, an eccentric mounted in said bar and engaging 35 said pivoted arm to move the same in the opposite direction against the tension of said resilient means, means for rotating said eccentric, and separating points carried by said arms.

40 3. A device of the character described, comprising a bar, a jaw member having its lower end slotted to accommodate said bar and provided with a socket opening into the upper wall of said slot, a pin forming a pivotal connection between the side walls of said slot and said bar, a spring disposed in said socket and engaging said bar upon one side of said pin, means for moving said jaw against the tension of said springs, and a 45 second jaw slidably mounted on said bar and opposing said pivoted jaw.

50 In testimony whereof I affix my signature in presence of two witnesses.

VICTOR W. MOORE.
